UNITED STATES PATENT OFFICE.

DE WITT C. PRESCOTT, OF CHICAGO, ILLINOIS.

POWER SET-WORKS FOR SAWMILLS.

No. 904,806.

Specification of Letters Patent.

Patented Nov. 24, 1908.

Application filed September 24, 1904. Serial No. 225,822.

To all whom it may concern:

Be it known that I, DE WITT C. PRESCOTT, a citizen of the United States, and resident of Chicago, county of Cook, and State of Illinois, have invented certain new and useful Improvements in Power Set-Works for Sawmills, of which the following is a specification, and which are illustrated in the accompanying drawings, forming a part thereof.

The invention relates to mechanism for advancing the knees of a saw-mill carriage, and particularly to the adjustable positive stop employed for limiting the stroke of a motor for driving mechanism of this character.

The invention consists in the device hereinafter described and claimed, and which is illustrated in the accompanying drawings, in which—

Figure 1 is a side elevation of the machine including a motor, some of the parts being broken away; Fig. 2 is a detail end elevation of the machine; Figs. 3, 4 and 5 are detail sections on the line 3—3, 4—4, and 5—5, respectively, of Fig. 2; Fig. 6 is a detail of one of the parts; and Fig. 7 is a detail section on the line 7—7 of Fig. 3.

Any form of motor may be employed, and the invention is not restricted to any particular form of mechanism for transmitting power from the motor to the set shaft.

There is shown in the drawings a reciprocating steam engine mounted upon a bed or frame 10, adapted to be attached to a saw-mill carriage, the cylinder of the engine being represented at 11, its steam chest at 12, the hand lever for controlling the throttle valve at 13, the shaft to which such lever is attached at 14, a crank mounted upon this shaft at 15, and the valve-stem of the motor connected with this crank at 16. The details of the engine are not shown, but the valve-gear is represented as of the type forming the subject of my Patent No. 745,520, of December 1, 1903.

A cross-head 17 is attached to the piston rod 18 of the motor and reciprocates upon the guide-rods 19, which are supported at one end by the cylinder and at the other upon an upstanding bracket of the bed 10. The cross-head 17 is provided with a gear-rack 20, engaging a segmental pinion 21, mounted upon a rocker shaft 22, which carries a pair of oppositely directed crank-arms 23, 24, connected by means of links 25, 26,

with a pair of pawl carriers 27, 28, mounted to oscillate upon the set shaft 29 and carrying pawls engaging the ratchet wheel 30 upon the same shaft. This transmission mechanism is also of common construction and is not of the essence of the invention. The cross-head 17 carries a head 31, located between the guide rods 19 and adapted for contact with the positive stop for determining the stroke of the motor. The stop with which the head 31 co-operates is shown at 32, and is located between the guide-rods 19 and keyed upon a shaft 33, journaled within suitable boxes carried by the bracket of the bed-frame 10 upon which the outer ends of the guide-rods are mounted, the shaft being located approximately on the plane of the head 31. The stop 32 is in spiral or substantially convolute form, so that as the shaft 33 is turned a radius of the stop in line with the head 31 constantly varies in length, accordingly varying the stroke of the engine, which is limited by the engagement of the head with the stop. The stop is controlled by a hand wheel 34, fixed upon the shaft 33, and preferably provided with a plurality of knobs or hand-pieces 35, which may be easily grasped by the operator. The face of this wheel is provided with a scale, as shown at 36, co-operating with an indicator 37 mounted upon a bracket-arm 38 rising from the frame 10. A pawl 39, pivoted upon the bracket-arm 38, cooperates with ratchet teeth 44, also formed upon the rim of the wheel 34, for frictionally holding the wheel in an adjusted position. The pawl is shown as having a tail-piece 40 projecting downwardly past the rear face of the bracket arm 38, which is socketed to receive an expansion spring 41, which reacts against this tail-piece so as to hold the nose of the pawl into engagement with the ratchet teeth. The pawl is controlled by a cam 42, actuated by a lever-arm 43. Preferably the hand wheel 34 is also provided with an annular templet plate 45, secured to its inner face and projecting radially beyond the ratchet teeth 44. This plate is preferably of steel and quite thin, so that it may be easily cut with a file and will be notched, as shown at 46, as may be required by the exigencies of the particular situation in which the machine is to be used.

Usually a saw mill is operated for a considerable period of time in the manufacture of certain sizes of lumber, and the work in

the mill is facilitated if the setter is able to change the adjustment of the stroke of the setting motor without close attention to the scale. To this end the templet plate will be notched to correspond with the several sizes of material being manufactured, and as these usually number but three or four the operator can at a glance bring the wheel to any desired position.

- 10 The pawl 39 is provided with a single tooth 47, adapted to enter the notches 46, and while this tooth is riding on the smooth portion of the templet plate the pawl is held out of engagement with the ratchet teeth 44. 15 Preferably the latter teeth are V-shaped and merely supplement the tooth 46. When the templet plate is not attached to the wheel, however, it is controlled only by these teeth and their V-form permits the operator to 20 turn the wheel without lifting the pawl.

As shown at 46 the templet plate 45 is provided with series of three notches close together, as providing for setting the machine for the cutting of material to the exact size, 25 or slightly below or above that size,--it being the practice to thus vary the thickness according to the kind of lumber being manufactured. For the convenience of the operator a stop 48 may be provided for limiting the movement of the wheel 34, the latter carrying a pin 49 into the path of which the stop 48, shown as a bracket secured to a portion of the bed-frame 10, projects.

In the first adjustment of a cant upon the 30 head-blocks of a saw-mill carriage, the operator may desire to give the motor one or more short strokes to bring the cant to the exact position desired, and especially with inexperienced operators it is advisable to 35 provide a stop for the motor which will so limit its stroke that the pawls coöperating with the ratchet wheel 30 will move but a single tooth. In the present instance this is provided for by setting a screw-bolt 50 45 through the face of the stop 32 at its largest radius and providing the bolt with a lock-nut 51, by means of which it may be fixed in an adjusted position. This bolt may be so set that when it is in the path of the head 55 31 the stroke of the motor will be restricted as may be desired.

I claim as my invention—

1. In a saw-mill set-works, in combination, a reciprocating part, and a stop located in the path of such part and comprising a pivotal member, the periphery of which constitutes its abutting face and is substantially in the form of a convolute curve, whereby the finest adjustments may be attained by the pivotal movement of such part.

2. In a saw-mill set works, in combination, a reciprocating part, and a manually-controlled stop located in the path of such 60 part and comprising a pivotal member, the

periphery of which constitutes its abutting face and is substantially in the form of a convolute curve, whereby the finest adjustments may be attained by the pivotal movement of such part.

3. In a saw-mill set works, in combination, a reciprocating part, a stop located in the path of such part and comprising a pivotal member, the periphery of which constitutes its abutting face and is substantially 75 in the form of a convolute curve, whereby the finest adjustments may be attained by the pivotal movement of such part, and a hand-wheel mounted with the stop.

4. In a saw-mill set works, in combination, a reciprocating part, a stop located in the path of such part and comprising a pivotal member, the periphery of which constitutes its abutting face and is substantially 80 in the form of a convolute curve, whereby the finest adjustments may be attained by the pivotal movement of such part, a hand-wheel mounted with the stop and having a scale thereon, and fixed pointer coöperating with the scale.

5. In a saw-mill set works, in combination, a reciprocating part, a stop located in the path of such part and comprising a pivotal member, the periphery of which constitutes its abutting face and is substantially 95 in the form of a convolute curve, whereby the finest adjustments may be attained by the pivotal movement of such part, a hand-wheel mounted with the stop and having ratchet teeth, and a spring pawl coöperating 100 with the ratchet teeth.

6. In a saw-mill set works, in combination, a reciprocating part, a stop located in the path of such part and comprising a pivotal member, the periphery of which constitutes its abutting face and is substantially 105 in the form of a convolute curve, whereby the finest adjustments may be attained by the pivotal movement of such part, a hand-wheel mounted with the stop and having ratchet teeth, a spring pawl coöperating 110 with the ratchet teeth, a removable templet carried by the wheel and projecting above its teeth and adapted to have notches cut therein, and a tooth carried by the pawl and riding on the templet.

7. In a saw-mill set works, in combination, a reciprocating part, a stop located in the path of such part and comprising a pivotal member, the periphery of which constitutes its abutting face and is substantially 120 in the form of a convolute curve, whereby the finest adjustments may be attained by the pivotal movement of such part, and means for extending a portion of the periphery of the stop.

8. In a sawmill set-works, in combination, a reciprocating part, a stop located in the path of such part and comprising a pivotal member, the periphery of which consti- 130

tutes its abutting face and is substantially in the form of a convolute curve, whereby the finest adjustments may be attained by the pivotal movement of such part, and a screw-bolt set in and projecting from the periphery of the stop.

9. In a saw-mill set works, in combination, a reciprocating part, and a pivotally-mounted stop in the path of such part, the

periphery of such stop constituting its abutting face and being curved through gradually varying radii, whereby the finest adjustments may be attained by its pivotal movement.
